UNITED STATES PATENT OFFICE.

JOHN P. HOLLAND, OF NEWARK, NEW JERSEY.

SUBMERGIBLE TORPEDO-BOAT.

SPECIFICATION forming part of Letters Patent No. 472,670, dated April 12, 1892.

Application filed December 5, 1889. Serial No. 332,695. (No model.)

To all whom it may concern:

Be it known that I, JOHN P. HOLLAND, a citizen of the United States, and a resident of Newark, Essex county, New Jersey, have 5 invented certain Improvements in Submergible Torpedo Boats, of which the following is a specification.

My invention relates to the class of torpedo or gun boats commonly called "submerging" or 10 "submarine" boats; and the object of the invention is to provide a torpedo-boat that will combine with the maximum of protection for both boat and crew the necessary accuracy in steering, the greatest allowable speed, de- 15 structiveness, and steadiness, whereby it is possible to begin the attack at a distance of one to two thousand yards distance, and whereby, also, the boat may be brought near enough to a man-of-war to apply a submerged 20 or submarine torpedo with the minimum risk of injury.

My invention will be fully described hereinafter, and its novel features carefully defined in the claims.

25 In the accompanying drawings, illustrative of my invention, Figure 1 is a vertical longitudinal mid-section of the boat, except as to the stern portion thereof. The plane of this latter section is indicated by line *a a* in Fig. 30 2. Fig. 2 is a half-plan and half-horizontal section of the boat, the plane of the section being taken just below the deck of the boat or crown-plate of the shell. Fig. 3 is an end elevation designed to illustrate the form of 35 the bow or stem of the boat, one-half only being shown; and Fig. 4 is a similar view of the stern of the boat. Fig. 5 is a side elevation of the stern portion of the boat. Figs. 6, 7, 8, 9, 10, and 11 are cross-sections of the boat 40 in the several planes indicated by the lines *b*, *c*, *d*, *e*, *f*, and *g*, respectively, in Fig. 2. Fig. 12 is an enlarged sectional detail to be referred to hereinafter.

The form of the shell or body of the boat is 45 sufficiently explained by the drawings. The means of propulsion comprise twin screws 11, driven by engines 2, supplied with steam from boilers 3. The steam-boiler furnaces are provided with a smoke-stack 4, arranged 50 amidships. The boat is furnished with a rud-

der 5 for ordinary lateral steering. The armament of the boat comprises a submerged gun 6 at the bow, a submerged gun 7 at the stern, arranged between the screws 11, two inclined overwater-guns 8, directed forward and aft, 55 respectively, and a light rapid-fire gun 9 with a shield mounted on a platform near the stack and always above the water-level.

10 is the forward gun-room, 11 the aft gun-room, and 12 the central gun-room and cabin. 60 In the bow is a water-ballast chamber 13.

On the deck or upper part of the shell of the boat is mounted an armored caisson 14, which embraces the lower portion of the smoke-stack 4 and the air-shaft 15 adjacent 65 to the latter. The forward part of the caisson 14 is fitted up as a conning-tower 16 for the steersman, and the aft part of same provides a protected companion-way 17. Around the top of the companion-way is placed a platform 18, on which is pivotally mounted at the center the gun 9 for rapid firing.

On the deck of the boat and extending fore and aft is a narrow hollow superstructure 19, which is tapered laterally toward the bow and 75 stern to form a cut-water when the boat is submerged. This reduces the resistance to the motion of the boat.

In the ballast-chamber 13 are placed the compressed-air reservoirs 20. 80

In Fig. 1 the line *W L 1* indicates the normal water-line when the boat is not in action. The line *W L 2* in said figure indicates the water-line when the boat is submerged and prepared for action. The line *W L 3* in same 85 figure shows the water-line when the boat is in rapid motion and advancing to the attack.

With this brief description of the general construction of the boat, I will now proceed 90 to describe the manner in which the boat is submerged and controlled. The buoyancy of the boat is such that normally the water-line will correspond to line *W L 1*. To submerge the boat, water is admitted to the chamber 13 95 at the bow, which sinks it gradually to line *W L 2*, the water entering the superstructure 19 at apertures 21 therein placed close to the deck or crown-plate of the boat. The apertures 21 near the bow of the boat will be pro- 100

vided with valves or hinged covers opening outward. These will prevent the water from entering at said apertures when the boat is running ahead light or not submerged, and 5 will yet allow the water to flow freely out of the superstructure when the boat lifts, or is allowed to rise by the pumping out of the water-ballast from the chamber 13. The super- 10 structure is built higher at its center adjacent to the caisson in order that such part may remain empty and buoyant for a longer time than the end portions during the submerging operation, so that the boat may preserve an even keel while sinking. When rising this 15 same central part will be first emptied of water and lightened over the center of buoyancy of the vessel, and the vessel will thus rise on an even keel. The boat, submerged to the line W L 2, is ready to attack. Advancing 20 rapidly the bow is depressed through the me- 25 dium of a pair of vertically-operating rudders 22, placed at each side of the stern, as seen in Fig. 2. These rudders are fixed to a horizontal rock-shaft 23, which has a crank 24 in it 30 over the stern-gun 7. Coupled to this crank is a rod 25, which extends forward and is coupled to a rocking-lever 26. To the upper end of this rocking lever is coupled a rod 27, which is coupled at its forward end to an operating- 35 lever 28 in the conning-tower 16. There is a series of peep-holes, as usual, in the wall of this conning-tower to enable the steersman to direct the course of the boat through the me- 40 dium of the usual steering apparatus, and when he has headed the boat for the ship or other object of attack he uses the lever 28 to deflect the rudders 22 to the proper angle, when the forward motion of the boat will sub- 45 merge it to the line W L 3. The maximum degree of deflection of the rudders 22 will be primarily determined and a stop will be pro- 50 vided to prevent the operating-lever from being moved too far. The overwater-guns 8 may of course be fired at a greater range than the submerged guns 6 and 7; but the range or 55 distance will depend in a great degree on the size and character of the guns. The projectiles may contain high explosives, and any explosive, compressed air, &c., may be em- 60 ployed for firing the projectile. The rapid-fire gun 9 may be of any approved pattern. It is designed to be used to protect against attacks by torpedo or other boats.

My boat depends on the buoyancy of the 55 armored caisson, particularly the large portion of it inclosed by the superstructure, to prevent it from sinking to the bottom when submerged. In order to be effective for this purpose, its volume must be considerable— 60 say four to five per cent. of the total volume of the hull—and it must be placed over or slightly in advance of the center of displacement of the submerged hull. A smaller proportionate volume—one or two per cent., for example— 65 would be wholly ineffective for the purpose.

as the vertical motion caused by passing waves of considerable size would be apt to founder the vessel by submerging the top of the air-shaft and smoke-stack. A much larger proportionate volume for the caisson is also 70 inadmissible, for the reason that the increased weight of the armor could not be carried, and also for the reason that the increased bulk and width would increase correspondingly the width of the superstructure. The caisson 75 must have sufficient area in plan for a pilot-house, air-shaft, and smoke-shaft, and as the roof of the pilot-house must be armored and immovable companion-ways must also be pro- 80 vided in the caisson. The caisson should be 85 as narrow as possible in order that the cross-section of the surrounding superstructure which opposes itself to the progress of the vessel may be maintained at the minimum. I prefer to arrange the pilot-house, air-shaft, 85 smoke-stack, and companion-way in the order named, the pilot-house or conning-tower being in front. As the function of the super- 90 structure is in part to provide a cut-water for- 95 ward of the caisson, which latter would other- 99 wise offer too great resistance to the move- 100 ment of the boat through the water, it is in- admissible to increase the cross-section of the superstructure, for the reason that this would make the resistance above the axis of the 105 boat too great and increase the tendency of the boat to lift forward when under way.

In order that the boat may run steadily when submerged to line W L 2, equal moments of resistance to forward or backward motion 100 are provided above and below the boat's axis, which is in the plane of the screw-shafts and submerged guns. The upper moments of re- 105 sistance are calculated from this axis up to W L 2. When the boat is submerged to W L 3, thus putting five feet of water over its body or shell, the resistance offered by the submerged portion of the caisson between W L 2 and W L 3 to movement through the wa- 110 ter produces a force which tends to turn the boat about a transverse axis through the cen- 115 ter of buoyancy and lift its forward end. This tendency is counterbalanced by the inclined rudders 22. Should the boat happen to reach a greater degree of submergence than to W L 3, the moment of resistance above the axis will be increased, and the added pressure, act- 120 ing on the turret near its top, will cause an increased tendency in the boat to rise at its forward end. As it is important that this lifting force in case of excessive submergence shall be effective, the part of the caisson ex- 125 posed above W L 3 should be made as large as possible without increase of weight and the part exposed should be placed at a dis- 130 tance above the center of buoyancy approxi- 135 mately equal to the boat's depth. In this de- 140 sign the transverse section exposed or above W L 3 is eight per cent. of the entire trans- 145 verse section of the boat at this point, and this 150

I deem the minimum to be effective. This exposed portion is at a distance above the center of buoyancy about equal to the boat's depth. As a further protection against excessive submergence, the air-shaft and smoke-stack above the top of the caisson are made square or oblong in cross-section, in that, if submerged while the boat is advancing, their flat surfaces may offer such resistance to movement through the water as will serve instantly

to raise the forward part of the boat and prevent it from foundering. The lower portion of the smoke-stack and air-shaft will be built of metal strong enough to withstand the impact of the waves. The weight of the armored caisson 14 and the superstructure 19 will be counterbalanced by a corresponding weight or ballast 29, placed at the bottom of the boat.

20 The air-shaft 15 and smoke-stack 4 will be made strong enough to withstand the buffeting of the waves, and their stanchness may be increased by a triangular brace 30, connecting the superstructure 19 with said air-shaft.

25 It is possible that in action a line-shot may perforate both the air-shaft 15 and the smoke-stack 4, in which case the smoke and products of combustion would be drawn through the shot-holes and down the shaft into the boat.

30 To obviate this difficulty I leave a narrow space 31 between the shaft and stack, and arrange therein a slide or screen in the nature of a thin metal plate adapted to be pushed up from the cabin 12 far enough to mask or close the shot-hole in the stack and prevent the escape of gases thereat to any injurious extent. This slide may be constructed and operated in any convenient manner. In Fig. 1 I show

35 the screen or slide 32, provided with a stem 33, which extends through the deck of the boat down into the cabin or gun-room 12, passing through a packed opening or gland therein by preference in order to prevent leakage.

40 On the superstructure in front of the conning-tower is or may be placed a wave-cutter 34 in the nature of an angular plate adapted to cut and break the waves and prevent them from dashing into the sight-holes of the tower.

45 I have stated that one function of the superstructure 19 is to serve as a cut-water; but it has another important function. The apertures 21 in the superstructure are so small and so few in comparison with the capacity 50 of the superstructure that the latter fills and empties slowly, and thus the submergence of the boat will be effected gradually. When the superstructure is above the water-level, very little water will enter the superstructure 55 at these apertures from the dashing of the waves over the body of the boat.

In Fig. 12 I have shown the valve 35, that closes the forward apertures 21 in the superstructure. This view is on a larger scale than 60 the other figures.

As a bow-depressor, in lieu of the rudders

22, a shifting ballast-weight may be employed, arranged over the keel amidships and adapted to be moved forward, so as to depress the bow when the boat is going into action.

70 I have not deemed it necessary to illustrate or describe the mechanism for pumping or blowing the water from chamber 13, for steering, for ventilation, &c., as these may be of the usual or any kind.

75 Having thus described my invention, I claim—

1. A torpedo or gun boat provided with means for completely submerging its hull and having mounted on its hull, at its center, 80 a hollow armored air-tight caisson surrounding the smoke-stack, air-shaft, and companion-way, and having also mounted on its hull an enclosed superstructure having comparatively small apertures for the admission of water, 85 the said caisson serving to suspend the submerged boat by its buoyancy, and the said superstructure serving to gradually retard the sinking of the hull while being submerged.

2. An unarmored torpedo or gun boat provided with means for completely submerging its hull and having erected on its hull, at its center, a hollow and nearly-submergible armored air-tight caisson which provides the necessary buoyancy to suspend the hull in 90 the water at the proper depth and prevent it from sinking to the bottom.

3. A torpedo or gun boat provided with means for completely submerging its hull, having a hollow nearly-submergible air-tight 100 caisson on its deck, over its center of volume, which suspends said submerged hull by its buoyancy, and having companion-ways and air-tight doors in its deck leading from said caisson to the compartments in the hull.

105 4. A torpedo or gun boat provided with means for submerging its hull, having a nearly-submergible, hollow, and air-tight caisson on its deck, over its center of volume, to suspend it in the water, having air-tight doors 110 in its deck leading from said caisson to the compartments in the hull, and having on its deck a hollow covered superstructure with pointed ends and relatively small apertures in it to admit water, said superstructure 115 closing the lower part of said caisson.

5. A torpedo or gun boat having mounted on its deck a hollow and air-tight caisson arranged over its center of volume and a covered apertured superstructure which incloses 120 the lower part of said caisson and having within its hull a water-chamber of sufficient capacity to submerge the hull and superstructure and to nearly submerge said caisson, and means for filling and emptying said 125 chamber.

6. A torpedo or gun boat provided with means for submerging its hull and with vertically-operating rudders for depressing its bow when the boat is in motion and having 130 mounted on its deck a hollow and air-tight structure which projects upward and regu-

lates the degree of enforced submergence of the hull by its resistance and buoyancy.

7. A torpedo or gun boat having a smoke-stack and an air-shaft arranged side by side and provided with a screen to close a shot-hole therein, said screen being provided with means, substantially as described, for operating it from the inside of the boat.

In witness whereof I have hereunto signed my name in the presence of two subscribing witnesses.

JOHN P. HOLLAND.
